US0D1018097S

(12) **United States Design Patent** (10) Patent No.: **US D1,018,097 S**
(45) Date of Patent: ** Mar. 19, 2024

(54) **MASSAGE CHAIRS WITH DISPLAY DEVICE**

(71) Applicant: **Innovative Vending Solutions, LLC**, Clayton, NJ (US)

(72) Inventors: **Gregory Ruggiero**, Sewell, NJ (US); **Richard Ruggiero**, Sewell, NJ (US); **Jonathan M. Ruggiero**, Turnersville, NJ (US)

(73) Assignee: **INNOVATIVE VENDING SOLUTIONS, LLC**, Clayton, NJ (US)

(**) Term: **15 Years**

(21) Appl. No.: **29/722,739**

(22) Filed: **Jan. 31, 2020**

(51) LOC (14) Cl. **06-01**

(52) U.S. Cl.

USPC **D6/367**

(58) **Field of Classification Search**

(57) **CLAIM**

The ornamental design for massage chairs with display device, as shown and described.

DESCRIPTION

FIG. 1 is a front right perspective view of a first embodiment of massage chairs with display device showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the article that form no part of the claimed design.

1 Claim, 7 Drawing Sheets
